MACHINE FOR THE CONTINUOUS CASTING OF FILMS DIRECTLY FROM SOLUTION

Alvin M. Marks, Beechhurst, N.Y., assignor to Mortimer M. Marks, Beechhurst, N.Y.

Application June 16, 1953, Serial No. 362,043

8 Claims. (Cl. 18—15)

This invention relates to a machine for forming continuous, uniform foils from solution, and more particularly to the manufacture of a foil capable of plane polarizing light transmitted therethrough.

Previously known devices for continuously producing foils from solution have employed doctor blades, moving belts, troughs, drums, dipping, and the like. In each case, the article produced lacked the uniformity and optical qualities which are essential to the functions of the foils herein described. All of the prior art devices employ relatively complex coating structures having linear relative motion, which motion gave rise to periodical thickness variations or striae.

Accordingly, it is an object of the present invention to provide apparatus for applying a casting composition to a surface by using a flowing technique to produce a highly uniform coating thereon.

Another object of the present invention is to provide a device for producing foil, uniform and smooth throughout its structure.

A further object of the present invention is to provide means for producing extremely thin uniform foils having certain optical properties, continuously and directly from solution.

Another object of the present invention is to provide means for forming a light polarizing foil in a continuous operation from solution.

An object of the present invention is to provide a device for the rapid, continuous production of a thin polarizing structure on a supporting transparent foil.

A further object of the present invention is to provide apparatus for providing a solution which will pass directly into a substantially continuous polarizing crystal under certain conditions of operation, to be hereinafter described.

The invention consists of the construction, combination and arrangement of parts, as herein illustrated, described and claimed.

In the accompanying drawings, forming a part hereof, is illustrated one form of embodiment of the present invention, in which drawings similar reference characters designate corresponding parts, and in which:

Figure 1 is a somewhat diagrammatic vertical section, taken through a complete embodiment of a foil and light polarizing material-forming machine made in accordance with the present invention.

Figure 2 is a view in front elevation, taken on line 2—2 in Figure 1, looking in the direction indicated by the arrows.

Figure 3 is a fragmentary view, somewhat enlarged, taken at the foil deposition station in the present invention.

Referring to Figures 1 and 2, 10 indicates a large disc which may be of the order of 6 to 12 feet in diameter, comprising a sheet of plate glass having a suitable thickness and a highly polished plane casting face thereon. For the purposes of the present invention it was necessary to provide a large, plane, chemically inert surface.

2

The disc 10 is suitably mounted for rotation, as for example, by means of a central opening 11 therein, within which there is disposed a hub 12. The hub 12 is provided with a rear flange A and a front flange B. The disc 10 is suitably cushioned and clamped between rubber sheets C, by means of bolts D which are inserted through holes drilled in the disc 10. The hub 12 is keyed to a shaft 13, which shaft is journaled within bearings 14 and 15. The bearings 14, 15 are carried upon a suitable support 16, which may be secured to a frame, generally indicated at 17 in Figure 1. The shaft 13 is driven from a source of power (not shown) which is linked by means of some suitable drive member, such as a chain and sprocket 18, to a worm 19, which engages a worm gear 20. The worm gear 20 in turn is keyed to the shaft 13.

The source of power (not shown) is applied to the driving mechanism through a variable speed drive device, so as to produce a slow but uniform rotation of the casting disc 10. For example, one complete rotation of the disc every thirty minutes may be desirable under certain conditions and with certain casting compositions. The period of revolution, however, must be variable so as to adapt the device for the casting of a wide variety of materials under varying conditions of temperature, humidity, air flow, and the like.

The casting composition is brought to the disc 10 from a feed tank 21, best shown in Figure 2. The feed tank 21 is preferably located above the point of application, so as to permit a gravity flow of the casting composition through a feed line 22, and out of a nozzle 23, which is disposed so as to direct the solution at the casting disc 10. Alternately, suitable pumping means (not shown) may be used to force the casting composition through the line 22 and out of the nozzle 23. The nozzle 23 is provided with an adjustable orifice so as to render it capable of handling casting compositions having different viscosities, and to control the flow rate of the solutions.

As the casting composition leaves the orifice of the nozzle 23, which may be located at a point spaced from the bottom of the casting disc 10, as shown in Figures 1 and 2, it falls upon the said disc 10 and flows downwardly along the line indicated at 24 in Figure 2. Due to the angular velocity of the leading edge, the stream of the casting composition makes an angle with the vertical as it flows downwardly across the disc 10. The angle indicated at θ in Figure 2 will depend upon the speed of the disc 10, the viscosity of the casting composition, and the flow rate of said composition.

It has been found desirable to minimize the flowing rate so that the leading edge 24 of the flowing composition inclines to a maximum angle, while at the same time covering the entire surface between the point of application of the composition and the edge of the disc 10 below the nozzle 23. If the rate of flow is too slow, or if the speed of the disc 10 is excessive, the line of flow 24 will be irregular, giving rise to unstable flow conditions and to an uneven coating of the casting surface.

As the disc 10 rotates there will thus be formed an outer band 25 which is completely coated by the composition. The composition deposited upon the disc 10 is maintained in its fluid state during its passage through the first quadrant of the disc by reason of a baffle 26 which is disposed in front of the casting disc 10, so as to cover the first quadrant. The baffle restricts overevaporation of solvent, and enables the solution to flow without solidifying.

The casting material spreads uniformly and smoothly upon the disc 10, as a result of the fluid condition of the composition throughout its travel around the first

quadrant. The excess fluid drips off the edge of the casting disc 10 into a trough 27 located beneath the disc 10, to receive the said excess casting composition. The fluid passes from the trough 27 into a lower tank 28, whence it may be re-used after being passed through suitable filters (not shown).

By allowing the coating to flow in the manner described above, an extremely uniform coating may be produced on the face of the casting disc 10, which coating may have a thickness ranging from approximately .0001" to .0006" upwardly, as desired, depending upon the factors of viscosity, temperature, speed of deposition, and the like, as previously indicated.

As the coated portion 25 of the disc 10 emerges from behind the baffle 26 into the second quadrant 29 of the disc's travel, the solvent within the coating composition begins to evaporate. The evaporation of the said solvent continues throughout the passage of the coated band 25 through the third quadrant 30 of the disc's travel. As the partially dried composition 25 reaches a point approaching the end of the third quadrant 30, and while it is still in the form of a viscous solid solution, it is pulled from the casting surface of the disc 10. The point at which the solid solution leaves the disc 10 is hereinafter referred to as the "take-off" point, and is generally indicated at 31 in Figures 1 and 2.

By reason of the fact that the casting composition flows upon a rotating casting surface, the direction of flow is caused to change continually. As a result, the striae, which usually form in films flowing in only one direction, are greatly minimized. Such irregularities as may remain in the flowing operation are almost completely eliminated at the film take-off point, hereinafter more fully set forth and described.

The composition is flowed upon the casting surface near the bottom of the casting disc 10, and is pulled from the disc 10 at a point roughly 270° removed from the casting station, in a direction which is at right angles to the direction of the striae. As a result of this arrangement, the take-off force tends to stretch the film at approximately right angles to its original flow-off direction and thus eliminate said striae from the film, thereby producing film uniformity hitherto unobtainable by previously known film casting devices.

While the casting disc 10 has been illustrated and described as being vertically disposed, it is within the purview of the present invention to employ other angles of inclination for the casting disc, it being one of the purposes of this invention to provide a film forming structure which will cause a radial flow of casting solution directed thereon so as to form a uniform film upon the existing surface, and at the same time dispose of surplus casting composition material.

The manner in which the solid solution film 25 is deposited upon a supporting base 33 is hereinafter more fully described.

Referring again to Figure 2, there is shown an enclosure 34 which surrounds the casting disc 10 and the apparatus which governs the deposition of the casting composition upon the said disc. An input air duct 35 is led into the enclosure 34 and an air-exhausting duct 36 is provided at another point in the wall of said enclosure. A flow of air, free from foreign particles, and having a suitable air speed, temperature and humidity, is led into the enclosure 34 by way of the duct 35. The air is directed across the face of the disc 10, in the second and third quadrants thereof, for the purpose of aiding the evaporation of the solvents from the band 25 of the casting composition. The solvent-laden air is thereafter drawn from the enclosure 34 through the duct 36.

At a point spaced from the end of the third quadrant 30 and just above the take-off point 31, there may be provided suitably spaced knives 37 and 38, located near the inner and outer edges of the casting band 25. The knives 37, 38 are spring-loaded so as to cut through the

band 25 and control the width of the strip of film 32 that is pulled from the disc 10. The excess material which lies between the knives 37, 38 and the edges of the cast material 25, is picked up upon a wind-up roll shaft 39, best shown in Figure 1. In this manner all of the material which has been cast upon the disc 10 is removed therefrom before the said disc passes into the fourth quadrant 40, after which, additional casting solution is deposited thereon from the nozzle 23. It will be seen that a continuous film 25 may thus be cast directly from solution.

Referring again to Figure 1, there is shown, in somewhat diagrammatic form, apparatus capable of taking the film 25 cast upon the disc 10 and depositing it upon a support 33. At the same time it is possible, as herein-after set forth, to render the film 25 capable of plane polarizing light.

In forming the film 25 into a plane polarizer, the base tape 33 of the take-off portion of the present apparatus, which pulls the film 25 from the casting disc 10, is driven at a speed substantially greater than the travel of the disc. Thus, for example, with the casting composition described below, a take-off speed of approximately five times that of the linear mean circumferential speed of the disc 10 has been employed. This differential in speeds provides a linear extension of the film 25 by a factor of approximately 5 to 1, and to an extent sufficient to align and crystallize the molecular structure of the film 25 at the point indicated at 41 in Figures 1 and 3, which is the place of deposition of the film 25 upon the supporting structure 33.

The extension of the film by a factor of approximately 5 to 1 converts the film into a crystal having the inherent properties of polarizing light. It will thus be seen that there have been provided means for directly converting a solution into a light polarizer directly from said solution onto a support member.

Referring again to Figure 1, there are shown a series of rollers by means of which the film 25, taken from the casting disc 10, may be handled throughout the various coating and drying operations necessary to finish the said film. The aforementioned rollers are driven by a common chain and sprocket drive (not shown), the sprockets being attached to the roller shafts. The supporting film 33, which may be cellulose acetate or some other transparent, translucent, or suitable material, is maintained under tension by means of a friction drum 42, which is connected to the feed roller 43. In this manner the supporting material 33 is caused to travel forward uniformly over all of the rollers, and carry thereon the film 25 throughout the various stages, hereinafter described, until it is finally wound upon the roll indicated at 61 in Figure 1.

After the supporting material 33 leaves the roller 43, it is coated on one surface with suitable coating material 45. The coating 45 is applied by means of a coating roll 46, which revolves within a feed tray 47, which tray is supplied with a continuous quantity of coating material from a reservoir 48 of such material by way of a line 49, leading from the reservoir to the tray 47. The coating roller 46 revolves in a clock-wise direction in Figure 1, at a speed somewhat greater than the linear speed of the supporting material 33. As a result of the differential in speed of the supporting material 33 and the roller 47, there is created a capillary, generally indicated at 50, which is defined by the closest proximity of the roll 46, to the supply material 33. No actual contact is necessary between the roll 46 and the supporting material 33, the small gap therebetween being bridged by the coating material in the form of the capillary 50.

The coating material 45 is partially dried in its forward travel over the succeeding rolls 52 and 53. Thereafter, and while still containing solvent and capable of flow, the supporting material 33 with its coating 45 there-

on, is brought into contact with the film 25 comprising the solid viscous solution taken from the casting disc 10.

The support member 33 is brought into contact with the cast film 25 coming from the glass disc 10, as the support member 33 reaches the roll 54. A fragmentary view somewhat enlarged, of the process at this stage is shown in Figure 3. As the supporting medium 33, and the cast film 25 reach the roll 54, they are both traveling downwardly, but with differing linear speeds, the linear speed of the supporting film 33 being considerably greater than that of the travel of the mean circumference 32 of the disc 10. Thus, for example, the speed of the supporting medium 33 may be faster than that of the film 25 by a factor of 5 to 1. As a result of the differential in speed, and the joining of the film 25 to the supporting medium at 41, the cast film is subjected to a linear stretch. The film 25 contains a considerable amount of solvent at this stage of the process, which allows the linear high polymeric molecules contained within the membrane to flow viscously into parallel relationship. Slip during the stretching stage compensates for the difference in linear circumferential speeds on the inside and outside of the band 25 coated upon the disc 10. The resulting properties as to orientation, polarization, and thickness, are substantially constant across the width of the film 25. Evaporation of the solvent from the cast film continues as indicated by the arrows in Figure 3, throughout the stretching process, and after the said cast film 25 is secured to the supporting medium 33, as indicated below the roll 54.

At the region where the stretched cast membrane 25 comes into contact with the supporting medium 33, the coating material 45, which still contains a considerable amount of solvent, flows into the interstices at the place of joining, generally indicated as 41a in Figures 1 and 3. The air is thereby excluded from the joint between the film 25 and the supporting medium 33.

After the cast film 25 is stretched and deposited upon the supporting medium 33, as previously described, the assembly is passed around a roll 55, and thence upwardly into a heated enclosure 56, within which the evaporation of excess solvent is substantially completed, and the linear molecules of the film 25, due to the elimination of said solvent are caused to lie in close parallel relationship. Thereupon, the forces of crystallization establish the molecules into a regular lattice. It is within the purview of the present invention to lead the film and supporting medium assembly from the heating chamber 56 over a roller 57, and into a second capillary coater 58, comprising a coating wheel 59, moving within a feed tray 60, which tray is fed by a constant supply of coating material (not shown). By this means a top coating of lacquer of some suitable composition, which may be for example, a nitrocellulose lacquer, may be applied over the crystallized and oriented film 25, for the purpose of protecting or stabilizing the said crystal. Following the coating operation, the dried film may be wound upon a take-up roll 61.

Where it is desired to produce from the cast film 25 a continuous crystalline light polarizing coating after deposition upon the supporting medium 33, it is necessary to provide a chemical composition by way of a casting solution, for this purpose. The casting solution must contain linear high polymeric molecules capable of crystallization upon extension, containing reactive side groupings, such as hydroxyl groups. The solution must also contain polarizing substances, capable of inter-crystallizing with the high polymeric molecules, such as iodine or known dyestuffs. It has also been found desirable to include cross-linking agents such as tetra ethyl ortho silicate, capable of reacting with a side grouping of the said polymeric molecular chain, and thus cross-linking them in whole or in part, in any direction normal to the direction of the stretch of the film 25.

The adhesive coating 45 may contain further quantities of cross-linking agents, to approximately saturate any other side chain reactive groups, encountered in the

stretched film 25. The elevated temperature during the final heating stage within the chamber 56 tends to drive off excess solvent which may contain uncombined excess tetra ethyl ortho silicate. These solvents are caused to evaporate through the deposited stretched film 25 from the underlying supporting medium 33, and those components not reacting with the reactive side chain groups of the polymeric chain, or with the other components present, are driven off in the form of a vapor.

If iodine is the active polarizing agent in the film 25, this too may be present in excess, and the excess uncrosslinked polarizing component may also be driven off within the heating chamber 56.

The casting solution contains a linear polymeric structure material such as polyvinyl alcohol, cellulose hydrate, gelatin, carboxy methyl cellulose, cellulose acetate butyrate, or the like, to which is added a suitable acid such as acetic acid, propionic acid or butyric acid. Suitable solvents such as ethyl alcohol, water, or esters are employed to aid in the solution of the linear polymers and dyestuffs employed in the composition.

In addition, a material capable of polarizing light, such as iodine or certain well known dyestuffs, may be employed in the casting composition. Those materials should be soluble, compatible, and capable of intercrosslinking with, or forming a dye-complex with the high polymeric component employed. It has been found desirable to employ a cross-linking material in the casting composition so as to stabilize the polarizing film cast therefrom. Tetra ethyl ortho silicate, boric acid, glyoxal, and other cross-linking substances, known to the plastics art, may be employed for this purpose.

Example of polarizing solution

The following comprises a suitable solution and method of preparing same for use in conjunction with the present machine:

Solution A.—Mix 1,000 parts by weight of polyvinyl alcohol powder into a slurry with 4,000 parts by weight of ethyl alcohol. While stirring, add 500 parts of glacial acetic acid and 4,500 parts of water to make a total of 10,000 parts. Heat while stirring to 80° C. to form a clear solution.

Solution B.—To 500 parts of ethyl alcohol, add 100 parts of iodine resublimed; heat to 70° C. until dissolved, and filter.

Solution C.—To 4,850 parts of Solution A, add, while stirring and while at 80° C., the following:

50 700 parts by weight of glycerin
1650 parts by weight of glacial acetic acid
50 parts by weight of water
50 parts by weight of tetra ethyl ortho silicate
2700 parts of solution B at 70° C.

55 Stir and filter under pressure, and thereafter allow to cool to room temperature.

The composition is then in condition to be used for casting directly upon the disc 10, from the nozzle 23.

60 In the use of the above-described composition, as set forth herein, a reaction occurs in which the OH groups of the polyvinyl alcohol react with the ethyl groups of the cross-linking compound tetra ethyl ortho silicate to convert the polyvinyl alcohol to a new material, herein termed "alkane silicate."

65 This reaction has been described in connection with United States Patent No. 2,432,113, dated December 9, 1947, issued to Alvin Marks, Gerhart Weiss, and Alvin Robert Miller. The reaction proceeds to completion in the course of the casting, stretching and heating process. While the reaction is relatively slow, as long as an abundance of solvent is present, after the film 25 is formed on the disc 10, and evaporation begins, the reaction proceeds more rapidly and thereafter goes to completion throughout the various stages of the process.

7
Example of base solution

The coating material 45, previously referred to in connection with Figures 1 and 3, preferably contains a cross-linking solution such as has been set forth above, capable of reacting with the polarizing film 25. A preferred coating material or base solution 45, suitable for use, as previously set forth, is as follows:

2330 parts by weight of a 30% solution of $\frac{1}{4}$ -second nitro-cellulose in butyl acetate
 4000 parts by weight of toluol
 4000 parts by weight of ethyl acetate
 1000 parts by weight of butyl acetate
 300 parts by weight of di-methyl-phthalate
 100 parts by weight tetra ethyl ortho silicate

In the polarizing solution set forth by way of example above, there is utilized as a solvent plasticizer, short chain components having the same general structure as long chain high polymeric molecules. For example, in the above formula, a high percentage of glycerin is employed. The glycerin acts as a solvent plasticizer. The glycerin also has reactive hydroxyl groups, capable of reacting with the tetra ethyl ortho silicate, and the hydroxyl group along the high polymeric carbon chain. Thus, the cast film 25, which may be initially highly viscous and capable of ready flow and extension, may become, after the alignment of its constituent long and short chain molecules and their subsequent reaction with the cross-linking agent, fixed and substantially non-extensible or retractable.

While the foregoing description has been largely devoted to the casting and forming of a light polarizing film, it is within the purview of the present invention to cast other solutions in the aforescribed manner, which solutions shall produce films capable of performing other light filtering functions.

Thus, for example, the films so produced may have the optical properties of producing relative retardation between the rectilinear components of polarized light, as in the case of $\frac{1}{4}$ or $\frac{1}{2}$ wave "plates." Such foils may also be only relatively slightly stretched and non-crystalline, and contain dyestuffs approximate to their action as optical filters, being thus made capable of absorbing a particular range of the spectrum, such as in the ultra-violet, visible, or infra-red spectrum.

In lieu of the flexible support member 33, described above, glass plates may be employed. The glass plates may be formed upon a suitable carrier member and the film 25 deposited directly on the surface thereof. In this manner a polarizing crystalline film surface may be deposited directly upon the glass plate.

It is also within the purview of the present invention to employ the above described device and process for the purpose of casting and producing continuous lengths of highly uniform film material, which material may have uses in the lamination of glass, or for various other purposes, where the high quality and uniformity, and low cost of the product produced by the subject-device and process, are required.

Having thus fully described the invention, what is claimed as new and desired to be secured by Letters Patent of the United States, is:

1. Apparatus for the continuous casting of flexible films from solution comprising, a source of casting material in solution, a rotatably mounted casting member in the form of a glass disc, a casting surface upon said casting member, a line connected at one end to the solution source and having its opposite end disposed so as to direct a stream of solution upon the casting surface, a source of rotary power connected to the casting member to continuously revolve the casting member past the dispensing end of the line and rolls adjacent the casting surface to remove the film therefrom after the solution has become sufficiently solidified.

2. Apparatus for the continuous casting of flexible

films from solution comprising, a source of casting material in solution, a rotatably mounted casting member, a casting surface upon said casting member, in the form of a vertically disposed glass disc, a line connected at one end to the solution source and having its opposite end disposed so as to direct a stream of solution upon the casting surface, a source of rotary power connected to the casting member to continuously revolve the casting member past the dispensing end of the line and rolls adjacent the casting surface to remove the film therefrom after the solution has become sufficiently solidified.

3. Apparatus for the continuous casting of flexible films from solution comprising, a source of casting material in solution, a rotatably mounted casting member in the form of a glass disc, a casting surface upon said casting member, a line connected at one end to the solution source and having its opposite end disposed so as to direct a stream of solution upon the casting surface, an adjustable nozzle upon the dispensing end of the line, a source of rotary power connected to the casting member to continuously revolve the casting member past the dispensing end of the line and means adjacent the casting surface to remove the film therefrom after the solution has become sufficiently solidified.

25 4. Apparatus for the continuous casting of flexible films from solution comprising, a source of casting material in solution, a rotatably mounted casting member in the form of a vertically disposed glass disc, a casting surface upon said casting member, a line connected at one end to the solution source and having its opposite end disposed so as to direct a stream of solution upon the casting surface, an adjustable nozzle upon the dispensing end of the line, a first source of rotary power consisting of a motor connected to a variable speed drive connected to the casting member to continuously revolve the casting member past the dispensing end of the line, a second source of power consisting of a second motor, a second variable speed drive connected thereto and rolls connected to the second source of power adjacent the casting surface to remove the entire film therefrom after the solution has become sufficiently solidified.

30 5. Apparatus for the continuous casting of flexible films from solution comprising, a source of casting material in solution, a rotatably mounted casting member in the form of a vertically disposed disc, a casting surface upon said casting member, a line connected at one end to the solution source and having its opposite end disposed as to direct a stream of solution upon the casting surface at a point spaced from the bottom edge of said casting surface, a source of rotary power connected to the casting member to continuously revolve the casting member past the dispensing end of the line and rolls adjacent the casting surface to remove the film therefrom after the solution has become sufficiently solidified.

35 6. Apparatus for the continuous casting of flexible films from solution comprising, a source of casting material in solution, a rotatably mounted casting member in the form of a disc, a casting surface upon said casting member, a line connected at one end to the solution source and having its opposite end disposed so as to direct a stream of solution upon the casting surface, a source of rotary power connected to the casting member to continuously revolve the casting member past the dispensing end of the line, and continuously change the direction of flow of said fluid during the initial portion of the casting operation, and rolls adjacent the casting surface to remove the entire film therefrom after the solution has become sufficiently solidified.

40 7. Apparatus for the continuous casting of flexible films from solution comprising, a source of casting material in solution, a rotatably mounted casting member in the form of a disc, a casting surface upon said casting member, a line connected at one end to the solution source and having its opposite end disposed so as to

direct a stream of solution upon the casting surface, a source of rotary power consisting of a motor connected to a variable speed drive connected to the casting member to continuously revolve the casting member past the dispensing end of the line, and continuously change the direction of flow of said fluid during the initial portion of the casting operation and rolls, and rolls adjacent the casting surface to remove the entire film therefrom in a direction substantially normal to the initial direction of solution flow on the plane of the casting surface after the solution has become sufficiently solidified.

8. Apparatus for the continuous casting and deposition of a crystalline light polarizing film from solution upon a support comprising, a source of coating material in solution containing linear high polymeric molecules capable of crystallization upon extension and a polarizing substance capable of intercrystallizing therewith, a rotatably mounted casting member in the form of a disc, a casting surface upon the casting member, a line connected at one end to the solution source and having its opposite end disposed so as to direct a stream of solution upon the casting surface, a first source of rotary power connected to the casting member to continuously revolve the casting member past the dispensing end of the line, and continuously change the direction of flow of said fluid during the initial portion of the casting operation, a second source of power, rolls adjacent the casting surface driven by the

10
5
10

second power source at a speed greater than the linear speed of the casting member to remove the entire film therefrom in a direction substantially normal to the plane of the casting surface, and impart a linear film crystallizing stretch to said film, a source of film support material, guide rolls between the support material source and the casting surface adapted to lead the said support material upon the film removing rolls and coating means between the support material source and the film removing rolls to apply a bonding solution to that surface of the support material which is brought into contact with the stretched film as they meet upon the film removing rolls.
